UNITED STATES PATENT OFFICE

2,411,499

SEWING MACHINE

Hubert Boothroyd, Leicester, England, assignor
to United Shoe Machinery Corporation, Flem-
ington, N. J., a corporation of New Jersey

Application June 29, 1945, Serial No. 602,197
In Great Britain July 19, 1944

6 Claims. (Cl. 112—35)

1

This invention is concerned with improvements in or relating to sewing machines and is particularly, but by no means exclusively, concerned with curved hooked needle chainstitch welt shoe sewing machines organized for sewing an inseam through an upper, a welt and an insole of a Good-year welt shoe; the term shoe used herein being intended to include outer footwear generally.

By way of example, the invention is herein illustrated as embodied in a welt and turn shoe sewing machine in which mechanism for supporting awl, needle and other stitch forming devices is arranged to cause the awl and needle to enter the work from the same side thereof and the chain of the inseam, i. e., the interlocking loops of thread, to lie on the welt.

One of the various objects of the present invention is to enable relatively movable parts of a shoe inseam sewing machine to be supported in the machine in such a manner as to prevent undesirable relative movement.

Another of the various objects of the present invention is to enable parts of a shoe inseam sewing machine which are particularly subject to relatively rapid wear to be readily and inexpensively renewed in a particularly convenient manner.

In the illustrative machine hereinafter described a needle support, a needle guide support and a channel guide support all form together a carrier movable towards and from the work about the same axis and in the direction of work feed so that a needle and a channel guide respectively secured on the needle support and channel guide support cooperate with an awl support comprising a second carrier similarly mounted in the machine to effect a continuous or substantially continuous feed of the work, the needle and channel guide carrier and awl carrier being mounted in readily removable bearings secured to the machine frame with fastenings common to more than one of the bearings to enable easy replacement.

In order to provide support for the needle and channel guide carrier additional to that provided by the removable bearings, the needle and channel guide supports are provided with inter-engaging portions arranged outside the circle of the needle as far as is convenient away from the axis about which these supports move. These portions, while they allow relative oscillating movement of the needle and channel guide supports about said axis, are arranged to prevent undesirable relative lateral or twisting or canting movements of the supports.

These and other features of the invention con-

2

sist in certain devices, combinations and arrangements of parts, hereinafter described and claimed, the advantages of which will be apparent from the following description taken in connection with the accompanying drawing.

In the drawing,

Fig. 1 is a left-hand view in side elevation of part of the illustrative mechanism;

Fig. 2 is a sectional view, taken on the line II—II in Fig. 1; and

Fig. 3 is a sectional view, in left-hand side elevation, of the illustrative mechanism taken on the line III—III in Fig. 2.

The machine illustrated in the drawing is a welt shoe inseam sewing machine of the general character of the machine described in United States Letters Patent No. 2,041,945, granted May 26, 1936, on application of Alfred R. Morrill, except that the machine of the present application is arranged, as in United States Letters Patent No. 1,920,998, granted August 8, 1933, also on application of Alfred R. Morrill, to lay the chain of the seam on the welt instead of in the channel of the insole of the shoe being operated on, as described in said first-mentioned patent.

The illustrative machine comprises a curved awl 1 secured in an awl support or carrier 3 arranged to oscillate about an axis 5 into engagement with a workpiece and away therefrom. The awl support 3 has extending from it cylindrical portions 7, 7 rotatably and slidably mounted in readily renewable bearings or bushes 9, 9. The bushes 9, 9 are secured in a bracket 11 which is fixed to the head of the machine by bolts, one of which is shown at 13. The bracket 11 has a portion 15 which connects the parts of the bracket 11 directly contacting the machine frame. The bushes 9, 9 each have a flange 17 extending therefrom, which flanges are secured by fastening screws 19, 19 to the frame bracket 11. The awl support 3 is moved to and fro in the line of feed by cam-operated levers, portions of which are shown at 21, 21 which engage hardened discs 23, 23 in bores in the cylindrical portions 7, 7 of the awl support 3 and the awl support is oscillated about the axis 5 by cam-operated mechanism similar to that disclosed in Patent No. 1,920,998, referred to.

The curved hooked needle of the machine, indicated at 25, is mounted on a separate carrier and is secured in a needle support 27 which has projecting from it a sleeve portion 29 (Fig. 2) rotatably and slidably mounted in a readily replaceable bearing bracket 31 secured by the aforesaid fastening screws 19, 19 to the frame bracket

11. The screws 19, 19 are threaded into the bearing bracket 31 at one side of the frame bracket 11 and pass through clearance holes in the frame bracket 11 and flange 17 at the other side of the frame bracket 11, the undersides of the heads of the screws engaging the outer face of the flange. By this construction it is possible to renew the bearing bracket 31 and the bush 9 at the left side of the machine merely by removing the set of screws 19 at the left which form common fastenings for both the bearing bracket 31 and adjacent bush 9.

The channel guide 33 is secured on a channel guide support 35 which is mounted for oscillation relatively to the needle but forms a part of the carrier for the needle and channel guide together. The channel guide support has projecting from it a sleeve portion 37 rotatably and slidably mounted in a bracket 39, similar to the bearing bracket 31, secured to the bracket 11 by fastening screws in the same manner as that of the bearing bracket 31. The bearings for the awl carrier and the needle and channel guide carrier formed by the pair of bearing brackets 31, 39 and the adjacent pair of bushes 9 thus may readily be removed from the frame bracket 11 and renewed if the parts become worn, saving expense of replacing the larger and heavier parts of the machine. Renewing the bearing brackets when worn, also restores the axial alignment of the needle support and the channel guide support.

To provide additional support for the needle and channel guide carrier parts the channel guide support 35 has secured to it a block 41 having formed on it an arcuate guiding or rib portion 43 concentric to the axes of the needle and channel guide support sleeve portions 29, 37 which are themselves in axial alignment. The arcuate guiding portion 43 engages a groove 45 in the needle support 27, which is arranged as far as is convenient outside the circle of the needle from the axis of the sleeve portion 29. The arcuate guiding portion 43 has on it a face 47, at right angles to the axes of the sleeve portions 29, 37 and engages a face 49 on the needle support, which engaging faces prevent the needle support and channel guide support from separating movement axially away from each other. As shown particularly in Fig. 3, the arcuate guiding portion 43 is of such angular extent around the aforesaid axes that, after wear of the bearing in the bracket 31, the arcuate portion also prevents twisting or canting movement of the needle support in the bearing about the point of engagement of the needle in the work relatively to the channel guide during work feed and ensures that the portion 43 and groove 45 will be in engagement during the whole of the relative oscillating movement between the needle support and channel guide support about said axes.

The needle is equipped with the usual form of needle guide 51 secured to a needle guide support 53 positioned between the needle support 27 and channel guide support 35. The needle guide support is pivotally mounted on a bushing 55 having a tongue-and-groove connection to the needle support so that it rotates therewith. The block 41 spans the thickness of the needle guide support 53 and thus serves to hold all the parts of the needle and channel guide carrier together.

Passing through the sleeve portions 29 and 37 of the needle and channel guide carrier and the bushing 55 of the needle guide support is a spindle

57 which has on it a flange 59 engaging the end of the sleeve portion 37. At the end of the spindle 57 opposite the flange the spindle is secured to the sleeve portion 29 by a pin 61. The pin 61 and flange 59 on the spindle prevent relative axial movement between the needle, needle guide and channel guide support parts of the carrier but allow the supports to oscillate relatively about the axis of the spindle 57. At each end of the spindle 57 is a small block 63 arranged to be engaged by cam-operated levers, indicated at 65, acting to move the carrier for the needle, needle guide and channel guide to and fro in the direction of work feed. The needle, needle guide and channel guide are oscillated relatively to each other about the axis of the spindle 57 by cam-operated means, as described more fully in the patents above referred to.

The awl support 3 alone comprises the awl carrier and is separate from that formed by the needle and channel guide supports 27 and 35 together with the spindle 57 on which the needle, channel guide and needle guide are mounted. The construction and arrangements 20 of the carriers thus are compact, rigid and durable in use and serve in minor particulars to assist in assembling the various carrier parts and bearing members therefor during the manufacture of the machine. The construction of the arcuate 25 guiding portion 43 and groove 45, being remote from the spindle 57, obviously interferes in no way with the assembly of the needle and channel 30 guide supports and is conducive to an extremely rugged construction.

35 The nature and scope of the invention having been indicated and a particular embodiment thereof having been described, what is claimed is:

1. A chain stitch inseam shoe sewing machine having a frame member, stitch forming devices 40 in the frame member including a curved hook needle, an awl, a channel guide, and a carrier on which the needle and a second one of the stitch forming devices are mounted, and a separate carrier on which the third one of the stitch 45 forming devices is mounted, in combination with readily removable bearing members for said carriers secured in the frame member with a fastening common to more than one of the bearing members.

50 2. A chain stitch inseam shoe sewing machine having a frame member, stitch forming devices in the frame member including a curved hook needle, an awl, a channel guide, and a carrier on which the needle and a second one of the 55 stitch forming devices are mounted, and a separate carrier on which the third one of the stitch forming devices is mounted, in combination with readily removable bearing members for said carriers comprising a bearing bracket and a flanged bearing bush with a common fastening screw 60 passing through the flange of the bush, the frame member and the bearing bracket to secure said parts together.

65 3. A chain stitch inseam shoe sewing machine having a frame member, stitch forming devices in the frame member including a curved hook needle, an awl, a channel guide, and a carrier on which the needle and a second one of the 70 stitch forming devices are mounted, and a separate carrier on which the third one of the stitch forming devices is mounted, in combination with readily removable bearing members for said carriers comprising a pair of bearing brackets and a pair of flanged bushes with common fastening 75 screws, each passing through the flange of a

bush, the frame member and a bearing bracket to secure said parts together.

4. A chain stitch inseam shoe sewing machine having work feeding and stitch forming devices including a curved hook needle, an awl, and a channel guide mounted for relative oscillating movement, a carrier movable back and forth in the direction of work feed upon which the awl is mounted, a separate carrier movable back and forth in the direction of work feed comprising axially alined supports for the needle and channel guide, and a spindle for preventing a relative movement from axial alinement between the needle and channel guide supports, in combination with interengaging portions on the needle and channel guide supports outside the circle of the needle for preventing axial movement of the needle support relative to the channel guide during the whole of the relative oscillating movement of said supports.

5. A chain stitch inseam shoe sewing machine having work feeding and stitch forming devices including a curved hook needle, a channel guide, and a needle guide located between the needle and channel guide and mounted for relative oscillating movement, and a carrier on which the needle, channel guide and needle guide are mounted, including axially alined supports for

the needle and channel guide, and a spindle for preventing relative movement from axial alinement between the needle and channel and needle guide supports, in combination with rib and groove means on the needle and channel guide supports spanning the needle guide and preventing axial movement of the needle support relative to the channel guide support during the whole of the relative oscillating movement of said supports.

6. A chain stitch inseam shoe sewing machine having work feeding and stitch forming devices including a curved hook needle, an awl, and a channel guide mounted for relative oscillating movement, a carrier movable back and forth in the direction of work feed upon which the awl is mounted, a separate carrier movable back and forth in the direction of work feed comprising axially alined supports for the needle and channel guide, and a spindle for preventing a relative movement from axial alinement between the needle and channel guide supports, in combination with interengaging portions on the needle and channel guide supports remote from said spindle for preventing relative axial movement of separation between said supports.

HUBERT BOOTHROYD.
